[57] CLAIM

The ornamental design of a magnetotherapy pad, as shown and described.

DESCRIPTION

FIG. 1 is a perspective view of a magnetotherapy pad showing my new design;

FIG. 2 is a top view thereof;

FIG. 3 is a bottom view thereof;

FIG. 4 is an end view thereof, the opposite end view being the same; and,

FIG. 5 is a side view thereof, the opposite side view being the same.

The broken line showing a strap is for illustrative purposes only and forms no part of the claimed invention.
